UNITED STATES PATENT OFFICE.

HERBERT R. NEVENS, OF MELROSE, MASSACHUSETTS, ASSIGNOR TO NEVENS-WALLACE
TRAIN CONTROL COMPANY, A CORPORATION OF MASSACHUSETTS.

AUTOMATIC BRAKE-SETTING DEVICE.

1,174,019.

Specification of Letters Patent. Patented Feb. 29, 1916.

Application filed June 19, 1911. Serial No. 634,010.

To all whom it may concern:

Be it known that I, HERBERT R. NEVENS, a citizen of the United States, residing at Melrose, county of Middlesex, Commonwealth of Massachusetts, have invented certain new and useful Improvements in Automatic Brake-Setting Devices, of which the following is a specification.

This invention relates to brake setting devices and particularly to a device for setting the air brakes of a railroad train and for accomplishing this purpose also through the medium of a certain novel portable track plate. In my prior Patent No. 739,907, September 29, 1903, I set forth a construction for this general purpose and explained therein the particular objects of the invention. These objects, as stated therein, have particularly to do with providing a means by which one of the crew of another train might stop an on-coming train without depending upon the uncertainty of signals.

One of the difficulties attendant upon the construction disclosed in my said former patent, and also I believe common to other devices known in the art, has been the effect of snow, ice or other substance lying upon or closely adjacent to the rail. This discovery has led to my present combination, in which I so relatively position the parts that a wheel, as for instance one of the wheels of the pony truck, as shown in the drawing, guards and breaks away for the tripping lever or whatever suitable mechanism is to be used. I have, furthermore, devised a track plate capable of combination with such a construction, the principal feature of the same being its capability of yielding to the passage of the wheel while immediately becoming effective upon the braking mechanism which follows the wheel.

The construction and operation of my device will be more fully described in the specification which follows. In that specification and in the drawings which form a part of it I have described and illustrated a form which I find well adapted to practical use and which I have set forth and discussed in detail as well illustrating the principles of my invention.

Throughout specification and drawings like reference numerals are employed to indicate corresponding parts and in the drawings:

Figure 1 is a side elevation of a locomo-

tive equipped with my device, Fig. 2 a rear view of the pony truck showing the tripping mechanism, Fig. 3 a plan view of the same, Fig. 4 a portion of a rail in side elevation with my movable track plate applied, Fig. 5 a plan view of my track plate upon a rail, Fig. 6 a sectional view of the plate on a rail, Fig. 7 is an enlarged view corresponding to Fig. 2, showing in further detail the operating mechanism and indicating the position of the regulator. Fig. 8 is an enlarged side view of a wheel with the tripping arm behind it, and Fig. 9 is a fragmentary sectional view of one end of the tripping arm and the valve taken on the line 9—9 of Fig. 8.

Upon suitable brackets 1, bolted to the frame of a pony truck or any other convenient truck on a locomotive tender or car, I provide bearings 2. Journaled in these bearings 2 is a shaft 3 upon each end of which is set an arm 4 adjustable by a screw connection and held by a lock nut 4¹. The arms 4 are set to the gage of the track so as to come directly over the center of the rail and follow directly behind the wheel W. The shaft 3 is hollow having within it a rod 30 upon which a pin 31 passes through a slot 32 cut in the shaft 3. At its outer end the rod 30 is exposed in a head 33 to which access may be had for restoring the parts of the adjusting device to its normal position. This adjusting device consists of a slideable sleeve 40 having a somewhat conical surface. The sleeve 40 is connected to the shaft 3 by a clutch 41 so that when the rod 30 is pushed in to restore the valve connections the shaft 3 will also be locked to it so that the arms 4 may be swung back to their normal vertical position. The slideable sleeve 40 is connected by links 42 with a fixed sleeve 43 which is held fast on the shaft 3. Between the several pairs of links 42 are weights 44. The connections between the sliding sleeve 40 and the fixed sleeve 43, therefore, constitute a device in the nature of a ball governor.

The operation of this part in brief is as follows:—When the arms 4 are tripped the shaft 3 will be rotated, thus imparting a rotation to the weights 44. This rotation of the weights 44 under the centrifugal action draws up on the links 42, disengaging the clutch 41 and sliding the sleeve 40 past the stem 50 of the valve 51 which opens the air systems of the train brake. It will be seen

that the centrifugal action of the weights 44 will depend upon the rapidity of the throw of the lever 4. The parts are so adjusted that when moving at ordinary speed the arm 4 will be tripped so as to impart such a revolution to the weights 44 as will only partly draw the sleeve 40 past the valve stem 50. That is to say, only the less steep part of the double cone shown in Fig. 9 will become effective upon the stem 50. This will give the ordinary or service application of the brakes. If, however, the train is running at high speed and the arm 4 be tripped, the weights 44 will be given a more violent rotation and thus be acted upon with greater centrifugal force, throwing the sleeve 44 a greater distance and bringing the steeper part of the cone surface of the sleeve under the valve stem 50, thus applying the emergency pressure to the brakes and bringing the train to a more sudden stop.

The valve construction may be of any suitable type but I have shown a casing 52 having a spring 53 surrounding the upper part of the stem 50. The pipe 54 leads to the pressure tank 55 which is connected in the usual manner with the brake system 56.

My tripping plate may be made in various forms but in Figs. 4, 5 and 6 I have specifically illustrated a preferred form which consists of a plate 60 adapted to rest upon the tread of the rail. On each end it has a tapered portion 61 so that the plate may be applied to rails of varying width. The plate 60 has a down turned flange 60¹ and to this on each side is pivoted the ends of a leaf spring 62. The plate 61 is cut out in the middle part of its upper face and across this is set a bridge 63 supported at each of its ends by the springs 62. The bridge, therefore, is capable of being pressed down flush with the plate 61 by the wheels but will immediately rise upon the passage of the wheel ready to engage the arm 4 which follows the wheel.

My device as described will be used in the following manner:—A brakeman is sent back, as usual. He carries with him the light portable track plate 60 which he applies to the rail at a suitable distance from his own train. If now a following train attempts to run by him without heeding his ordinary signals, either through the inability of the engineer to see his signals or through disregard for the same, the track plate 60 will be encountered. The wheels of the engine run over the tapered end 61 of the plate 60 and strike the bridge 63 which is depressed but rises again promptly after the passage of each wheel. In the form shown, the bridge will be depressed by the wheels of the pony truck but immediately upon the passage of the second wheel would rise to encounter the arm 4 which it will trip. As above described, this tripping

motion of the arm 4 will be more or less sudden, according to the speed at which the engine is running. If the engine is running at low speed the arm 4 will be tripped comparatively slowly, thus sliding the sleeve 40 only a short distance and applying the ordinary service pressure to the brakes. If, however, the train is running at high speed the arm 4 will be tripped violently throwing out the weights 44 to their extreme position and bringing the steep pitch of the cone of the sleeve 40 under the stem 50, thus opening the air system for an emergency application of the brakes.

While I have discussed and claimed my invention in the terms of its application to the present railway system, it will be understood that it may be applied to any system of this nature and that the terms employed should be so construed.

Various modifications may obviously be made in the form of rail plate, in the location of the tripping lever upon different wheels, and the specific connection and construction of the parts. The governing device may also be obviously varied or may be omitted although I find the same to be of great value in giving practical service as it is not, of course, advisable to give an emergency application of the brakes unless absolutely necessary. All these various modifications are asserted to be within the scope of my present invention if within the limits of the appended claims.

What I, therefore, claim and desire to secure by Letters Patent is:—

1. In combination with a brake system a device for automatically setting air brakes by contact with a track obstacle applied to the rail tread comprising a trip mounted behind the wheel and positioned directly over the tread of the rail, said trip being operatively associated with the brake system to set the same upon contact with the track obstacle.

2. Automatic air brake mechanism for railroad trains comprising a track obstacle adapted to be applied to the rail tread and means operable by said track obstacle located over the rail and behind a wheel for causing the application of the brakes.

3. In combination with the relief valve of an air brake system, a normally inert relief mechanism in operative association therewith, a track obstacle, and a train carried tripper effective upon contact with said track obstacle to overcome the inertia of said relief mechanism, and impart to it a velocity proportionate to the velocity of the train whereby the air valve is relieved in a degree proportionate to the velocity.

4. In a device for automatically setting air brakes on a railroad train the combination of a valve for relieving the pressure on the train line pipe, a centrifugal device, op-

erative connections between said centrifugally moving device and said valve, tripping means located behind a wheel for imparting to said centrifugally moving device a rotative tendency, a rail plate, and a yielding tripper on said plate.

5. In a device for automatically setting air brakes on a railroad train the combination of a valve for relieving the pressure on the train line pipe, a shaft, a centrifugally moving device on said shaft, operative connections between said device and said valve, a tripping arm on said shaft and located behind a wheel for imparting to said centrifugally moving device a rotative tendency, a rail plate and a yielding tripper on said plate and adapted to engage said arm.

6. In a device for setting the air brakes of a train, the combination of a valve for relieving the pressure on the train pipe, a centrifugally moving device, operative connections between said device and said valve for actuating the latter, and means positioned exteriorly of the train for imparting a rotative tendency to said centrifugally moving device.

7. In a device for setting air brakes on a train, the combination of a valve for relieving the pressure on the train pipe, a shaft, a centrifugally moving device on said shaft, operative connections between said centrifugally moving device and said valve to actuate the latter, and a tripping arm on said shaft for imparting thereto a rotative tendency.

8. In a device for automatically setting air brakes on a train, the combination of a valve for relieving the pressure on the train pipe, a shaft, a centrifugally moving device on said shaft, a member mounted for relative movement longitudinally of said shaft, an operative connection between said centrifugally moving device and said longitudinally movable member for moving the latter, said longitudinally movable member being effectively associated with said valve to transmit thereto the movement imparted thereto by said centrifugally moving device.

9. In combination with a car brake system, a brake setting device comprising a centrifugal member, an actuating device for

the brake system operatively connected with said centrifugal member, and means operable exteriorly of said car for imparting to said centrifugally moving device a rotative tendency.

10. An automatic brake mechanism for railroad trains, comprising a yielding tripping means supported over a rail tread, a member located over the rail and behind a wheel and adapted for actuation by said tripping means, and means on the train operable by the actuation imparted to said member to cause the application of the brakes.

11. In a device for setting air brakes on a train, the combination of a valve for varying the braking pressure, a speed varied controlling mechanism on the train operatively associated with said valve to actuate it to a greater or less degree and an externally operated actuating device for said controlling mechanism variably operable according to the speed of the train.

12. In combination with the relief valve of an air brake system, a movable member having an operative actuating relation thereto, a train-carried tripping device effectively disposed to receive the force of an impact with a track obstacle, and means positively connecting said movable member and tripping device and effective at any degree of train speed and upon any impact of said tripping device with the track obstacle to impart to said movable member a degree of operative movement directly proportionate to the train speed at the moment of impact.

13. In combination with the relief valve of a braking system, means for actuating said valve to a greater or less degree proportionate to the speed of the train, a train-carried trip disposed for contact with a track obstacle, and means positively connecting said valve actuating means and said trip.

In testimony whereof I affix my signature in presence of two witnesses.
